UNITED STATES PATENT OFFICE.

JAMES A. HOUSE, OF BRIDGEPORT, CONNECTICUT.

KNITTING-MACHINE.

SPECIFICATION forming part of Letters Patent No. 542,055, dated July 2, 1895.

Application filed July 2, 1894. Serial No. 516,335. (No model.)

To all whom it may concern:

Be it known that I, JAMES A. HOUSE, of Bridgeport, county of Fairfield, State of Connecticut, have invented an Improvement in Knitting-Machines, of which the following description, in connection with the accompanying drawings, is a specification, like letters and numerals on the drawings representing like parts.

This invention has for its object to simplify and improve the knitting-machine shown and described in United States Letters Patent No. 479,986, dated August 2, 1892. The machine described in said patent contains a conical needle-bed provided at its upper end with a series of pivoted sinkers, the needles being moved in the grooves of the said bed by a cam-ring adapted to be rotated for circular knitting and to be reciprocated for narrowing and complementary widening, as when knitting heels and toes, said cam-ring containing crossing grooves, one being designated as the "knitting" and the other as the "non-knitting" and "topping" groove, said cam ring or plate having at the junction of the crossing grooves needle-selecting devices, whereby any desired needle of the entire series of needles may be employed as the first needle of a narrowing or widening course and any desired needles may be made to knit in the course and be then returned into the non-knitting groove before knitting a second narrowing or widening course.

It will be understood in the machine herein to be described that, in knitting, each needle, whether circular or flat work is being done, is taken from the topping or non-knitting groove into the knitting-groove, and, having made a stitch, is put back again into the non-knitting groove before making another stitch, the two grooves having a common crossing-point between the usual drawing-down cams, and at this crossing-point are located the needle-selecting devices, composed essentially of a somewhat triangular or heart-shaped directing-cam and two points, each directed toward the other and located at opposite sides of the point of the directing-cam, said selecting devices having relative movements one with the other, such as at times to open and close the passages leading from the non-knitting to the knitting groove. In this instance of my

invention I have chosen to show the directing-cam as pivoted and as movable only by the action of the butts of the needles against it and the points as being moved positively from devices outside the cam-ring; but this invention is not limited to imparting movement positively to a particular one of said devices, as it will be obvious that either the points having 55 the designating term "guiding-gates" in the said patent or the directing-cam might be moved positively, as in United States Patent No. 531,062, dated December 18, 1894, and effect the opening and closing of the passages 60 leading from the knitting to the non-knitting groove, and vice versa.

In accordance with my invention I have devised novel means for effecting this relative change of position of the points and the directing-cam to open and close the passages 70 leading from one to the other groove, according to whether it is desired to knit with the cam ring or plate moving in one or the other direction.

In the patent referred to the cam-ring was provided with a series of beveled teeth to be engaged by a bevel-toothed wheel, to thus impart movements to the cam-ring; but herein I have simplified that construction by providing 80 the lowerend of the cam-ring with a flange, which is secured to a toothed ring adapted to slide about the neck of the conical needle-bed, such construction greatly simplifying and reducing the expense of the machine.

The devices for effecting the relative change of position of the needle-selecting devices derive their movement from a lever device mounted upon the cam-ring, and this lever device must be moved at times in one and 90 the other direction, and this device must be moved sooner or later in the movement of the cam-ring, according to the number of needles to knit in a given course, the mechanism employed for effecting this purpose being designated broadly under the term "shogging mechanism."

The shogging mechanism represented in the patent referred to consisted essentially of two rings encircling loosely and carried by 100 the cam-ring, said ring having pins which were adapted to be moved by or through stop-rings mounted upon a part of the bed-plate, said stop-rings being moved in opposite direc-

tions by means of toothed gears adapted to be rotated in one or the other direction, as desired, the pins being thus made to approach each other or to separate one from the other, 5 according to the length of the course being knitted, so as to rotate a cam device carried upon the cam-ring. Instead of the four rings referred to I, in this instance of my invention, employ two rings provided with cams to co- 10 operate with a lever having toes and mounted upon the cam-ring.

In the patent referred to the hollow spindle on which are pivoted the thread-carrying arms, is rotated by a large gear mounted on a 15 shaft having a pinion engaged by a sliding rack having connected to it a shifting-bar located between two cam hubs or plates, and the shears are closed by a sliding wedge. Herein I have provided novel devices for ro- 20 tating the said hollow shaft and for operating the shears and have supported one of the thread-feeding rolls in a yielding bearing. I have also devised novel means for actuating the rack-bars of the shogging mechanism and 25 have provided means whereby the change of motion is effected at desired intervals by or through a pattern-surface.

Figure 1 is a left-hand side elevation of a knitting-machine containing my improvements, the framework being partially broken out, the needle bed being omitted, and the thread-feeding mechanism being also omitted; 30 Fig. 1^a, a detail to be described. Fig. 2 is a rear elevation of the parts shown in Fig. 1. Fig. 3 is a right-hand side elevation of the parts shown in Fig. 1, the circular curb and parts to contain the needle-bed being broken out. Fig. 4 is a top or plan view of the machine shown in Fig. 1 with the needle-bed and cam-ring in 35 place, together with the thread-guide for presenting thread to the needles, said figure being somewhat enlarged from the scale represented in Figs. 1 to 3. Fig. 5 is a sectional detail through part of the machine shown in Fig. 4 in the line $x-x$ of that figure, the portions of the machine outside of the curb, to be described, being omitted. Figs. 6 and 7 are 40 details to be referred to of parts carried by the main shaft and instrumental in changing detail from rotary to reciprocal knitting, and vice versa. Fig. 8 is a top view of the bed-plate of the machine and the parts attached thereto below its top, said figure showing the spider for receiving the neck of the needle-bed. Fig. 45 9 is a detail to be referred to, it showing one of the guides for the curb in its vertical movements, and the raceway instrumental in changing the tension or length of loops to be knitted. Fig. 10 is a section in the line 50 x^2 , Fig. 9. Fig. 11 is a detail showing part of the cam-ring with its attached thread-guide. Fig. 12 is a detail showing part of the cam-ring opposite the thread-guide. Fig. 12^a shows one of the points or guiding-gates detached; Fig. 13, a detail showing the interior of the cam-ring at the point where the 55 knitting and non-knitting grooves cross, with

part of the ring containing the gates used to direct the needles from the knitting to the non-knitting grooves, and vice versa, for narrowing and widening and for circular work, as provided for in the Patent No. 479,986; Fig. 13^a, a detail of the slide for moving the points of the selecting device; Fig. 14, a detail showing the lever for moving the points; Fig. 14^a, a detail of part of the sinker-actuating cam-ring to show its adjustable shoes. Fig. 15 is a detail showing part of the devices instrumental in raising the curb. Fig. 15^a shows one of the strikers co-operating with 80 the lug on the sinker-actuating ring. Fig. 16 is a detail showing the lever device and cam instrumental in moving the lifting-circle. Fig. 17 is another view of the parts shown in Fig. 16. Fig. 18 is a detail showing the spline 85 227; Fig. 19, an enlarged right-hand side elevation of the thread-presenting mechanism omitted from Fig. 3; Fig. 20, an under side view of the thread-presenting mechanism shown in Fig. 19; Fig. 21, a rear end view of 90 the thread-presenting mechanism shown in Fig. 19; Fig. 22, a partial top view of the parts shown in Fig. 19; Fig. 23, an enlarged detail showing the thread-holding rolls. Fig. 24 shows a modified form of plate to be used instead of plate c^x of Fig. 22. Fig. 25, on an 95 enlarged scale, shows the gearing of the shogging mechanism; Fig. 26, a view of the parts shown in Fig. 25, looking from the left; Fig. 27, a section in the line x^3 , Fig. 26, the two 100 shafts 168 and 171 being shown in elevation; Fig. 28, a top or plan view of the parts shown in Fig. 27, some of the gears and the hollow shaft 164 being shown in section.

The legs or standards A, the power-shaft 105 g^{12} , driven in any suitable manner from a proper counter-shaft and having a set of fast and loose pulleys controlled by a belt-shipper g^2 , the gear h , fast on said power-shaft and engaging a larger toothed gear h' , fast on 110 the main shaft e^7 of the machine, the snail-wheel e^6 , adapted to engage the teeth of a gear e^5 on the monitor-shaft d^{12} , provided with a monitor-wheel adapted to receive and carry a pattern-chain 61, represented as a broad chain 115 having several rows of indications suitable to act upon the fingers arranged about it, as will be hereinafter described, said chain being but partially shown, the lever f^2 , controlled by said pattern-chain and moving the shipper-lever, the notched disk h^2 , also fast on said shaft e^7 and having alongside of it a gear h^3 , loose on said shaft, the sliding plate or carriage h^4 , connected to said wheel h^3 and sliding therein transversely with relation to the 120 shaft e^7 and having a roller 22, which in practice is normally pressed outwardly through a notch in the flange 23^x of said wheel by suitable springs h^5 , said sliding plate having a coupling-pin 21, the shoe e^{14} , the vibrator h^6 , loose on the shaft e^7 and having a notch 23, adapted to be entered by the pin 21, said vibrator having a suitable locking-dog h^8 , which 125 in the rotation of the wheel h^3 is depressed

against its supporting-spring by the contact of the pin 21 against it as the said pin is pushed out of notch 16 in the wheel h^2 into said notch 23. The shaft h^{12} has fast on it a gear h^{10} and also has fast upon it the gear B^3 , having beveled teeth and adapted to impart rotary motion to the cam ring, the conical needle-bed A^3 , having a shank A^2 and provided with projections A^6 to guide a sinker-actuating cam-ring A^7 , the series of sinkers A^5 , made as levers and supported upon a suitable wire A^9 or equivalent device sustained in the upper end of the conical bed, each of said sinkers being adapted to move in a slot cut in the top of the bed between the usual needle-grooves, the raceway b^{13} , having a projection b^{14} , suitably joined by a link b^{50} to a block b^{14x} , adjustably held by screws in a slot of a pattern-finger f^2 (see Fig. 1) and adapted 15 in its rotation by or through the control of a pattern-chain to rise and fall, the tension-lever c , pivoted upon the cam-ring and having at one end a screw or equivalent device to ride upon the said raceway and at its inner 20 end engaging a pin on and moving the knitting-cam, to thereby cause it to move the needles to make a longer or shorter stitch for a slack course or for giving greater or less fullness to the knitting in the production of circular work, are and may be all substantially as provided for in the said patent, wherein like letters and numerals are used to designate the parts hereinbefore specifically referred to by letters and numerals. In this instance of my invention the vibrator h^6 derives its movement from the link k' , connected to an arm of a rock-shaft k^3 , having jointed to it a connecting-rod k^2 , fitted at one end over a crank-pin on a crank k^x , fast on 25 the continuously-rotated shaft e^7 , and when the coupling-pin 21 is in engagement with the vibrator h^6 then the vibrator oscillates the gear h^8 , and it, in engagement with pinion h^{10} , rotates the shaft h^{12} in one and then 30 in the other direction for reciprocal knitting or for knitting a flat web, as when narrowing and widening; but when the pin 21 of the plate h^4 enters the notch 16 of the continuously-rotating plate h^2 then the gear h^8 will 35 be rotated continuously for roundabout or circular knitting.

When knitting is to be changed from reciprocal to circular, the shoe e^{14} , connected to arm 232 of rock-shaft 233, is turned to throw 40 said shoe aside out of the path of movement of the roll 22, letting the springs h^5 act to pull the pin 21 from the notch 23 in the vibrator and cause it to enter notch 16 in the plate h^2 , said notch at that time being opposite the 45 notch 23. The shaft 233 is turned for the purpose stated by or through lever 235, then acted upon by spring 238. The lever 235 has at its end next the pattern-surface a pin 237, (see Figs. 2 and 15,) which is connected to a 50 pattern-finger b^{42} , (shown in Fig. 1,) the lever 235 being moved in a direction against the spring whenever a projection of the pattern-

chain 61 meets the finger b^{42} , such movement of the lever 235 causing the shoe e^{14} to be thrown into position to meet the roll 22 and 55 cause the pin 21 to leave the notch 16, and after the pin leaves said notch it travels over the surface of the locking-dog h^8 , which is normally held up toward the plate h^2 by a spring, and, passing said locking device, the latter 60 rises under the action of its spring and closes one side of the notch 23, so that the pin 21 during the oscillations of the vibrator h^6 is held firmly at each side.

The devices for moving shoe e^{14} will be here- 65 inafter described.

I have briefly referred to a means used to rotate continuously or in one and then in the opposite direction the shaft h^{12} ; but this invention is not limited to the employment of 70 the means shown for imparting the motions described to the shaft h^{12} , and instead I may use any other usual or suitable devices 75 commonly found in knitting-machines of the circular class adapted to automatically narrow 80 and widen for the production of heels and toes.

The table-top A^x , mounted on the legs A , has a flange 100, inside of which is fitted the raceway b^{13} , before described, it having a series of studs b^{12} , which enter inclined grooves of 85 cam-stands b^{10} , secured to the top plate, or a part thereof, by suitable screws 101. (Shown in Figs. 4 and 9.) This raceway will, in this present invention, be moved as and for the exact purpose fully set forth in said patent. 90

The table-top, attached to the legs by suitable bolts 105, as shown best in Figs. 8 to 10 and in Fig. 3, has a spider composed of depending arms 102, radial arms 103, and a ring 104, said spider for cheapness of construction, 105 durability, and stiffness being cast as an integral part of the table-top; but this invention is not limited to making the spider and the top in one piece.

The spider is shown as having attached to 110 it by screws 106 suitable bearing-trusses 107 to support parts to be described.

The depending arms 102 have attached to them steel guide-plates 108, having slots 109, which are entered by projections 110 (see Fig. 115 5) on a circular curb 112, containing the shogging or racking bars b^6 and b^9 , toothed at their under sides and corresponding substantially with the shogging-bars represented by like letters in said patent. In the said patent the 120 shogging-bars had only a motion in a circular path; but herein the shogging-bars are carried within the curb 112, and the latter has imparted to it at suitable times a vertical movement—that is, it occupies the position 125 shown by full lines in Figs. 3 and 5 when circular knitting is to be done—at which time the selecting devices carried by the cam-ring remain in the same position; but when narrowing and widening is to be done and when 130 only a part of the needles are to be used for each course of knitting then the curb is lifted quickly into the dotted-line position, thus enabling the cam projections 113, 114,

115, and 116 on the shogging-bars to be put into the range of movement of the toes 117 and 118, connected to a lever 119, mounted on a stud s^2 , connected to the cam ring or plate 5 B', the upper end of said lever having a compound cam-slot s^3 , which receives in it a stud s^3 , attached to a slide s^4 , fitted into a guiding-groove s^5 , cut transversely in the inner side of the cam-ring, (see Fig. 13,) said 10 slide having (see Fig. 13^a) notches s^6 , which receive projections s^7 (see Fig. 12^a) from the rear sides of the points a^7 a^8 , said slide when moved effecting the movements of said points.

As herein provided for, when the stud s^3 is 15 in the upper part s' of the said cam-slot the points a^7 a^8 will stand as represented in Fig. 13 with relation to the directing-cam a^{18} and will cause the butts of the needles to be moved from the non-knitting into the knitting 20 groove; but the directing-cam may touch either the point a^7 or a^8 , according to the direction of movement of the cam-ring.

When all-around or circular work is being knitted, the directing-cam will stand next the 25 point a^7 ; but when reciprocal knitting is being done the said directing-cam will rest in one direction of movement of the cam-ring against one and then against the other of said points.

30 When the stud s^3 stands in the lower part s of the compound cam, then the points a^7 and a^8 occupy their farthest position from the directing-cam and all the needles are put from the knitting-groove into the non-knitting 35 groove. The shogging-bar b^6 —the inner one—is engaged and moved by a pinion 161 and the shogging-bar b^9 by a pinion 162. The pinion 161 is fast on a shaft 163, while the pinion 162 is fast on a sleeve 164, surrounding 40 the shaft 163. The shaft 163 has a worm-toothed wheel 165 fixed to it, while the sleeve 164 has fixed to it a worm-toothed wheel 166, the worm-toothed wheel 165 being engaged and rotated by a worm 167, loosely splined on 45 a shaft 168, (see Fig. 27,) having an attached bevel-gear 169, the worm-toothed wheel 166 being rotated by a worm 170, loosely splined on a shaft 171, having an attached bevel-gear 172.

The bevel-gear 169 is engaged by two wheels 50 173 and 174, either of which may be the driver for the shaft 168, according to the requirements of the pattern-surface, for it will be understood that the gears 161 and 162 must be moved when narrowing is being done in 55 one direction intermittently and when widening is being done must be rotated in the opposite direction intermittently. The bevel-gear 172 on the shaft 171 is engaged in like manner by two gears 175 and 176, either of 60 which may be the driver for the shaft 171.

The vertically-movable curb 112 has bolted to it a stand 112^x, said stand having the bearings for the shafts 168 and 171 and also supporting between its upper and lower members 65 the worms 167 and 170, such construction enabling the curb to be moved up and down with relation to the shafts 168 and 171 and

yet always maintain the engagement of the toothed gears 161 and 162 with the rack-bars b^6 and b^9 .

The shaft h^{12} , (see Fig. 25,) which when circular knitting is being done is rotated continuously in one direction and which when reciprocal knitting is being done is rotated in one and then in an opposite direction, has fast on it 75 two pawl-carrying arms 302 and 303, each provided with two spring-controlled pawls, the said pawls being adapted to co-operate respectively each with its own ratchet-wheel 308 80 309 310 312, the ratchet-wheel 308 being fast to a hollow hub of the gear 174 and the ratchet-wheel 312 fast to the hub of the gear 175, said gears 174 and 175 being mounted loosely on like hubs 313 of a casting 314, surrounding the shaft h^{12} loosely, which latter is suitably supported in bearings of its own on the frame of the machine, said casting also having bearings for the shafts 168 and 171.

The ratchet-wheels 309 and 310 are secured respectively to the bevel gear-wheels 173 and 176, as shown, by like screws 313^x and 314^x, said gears being loosely mounted on the hubs of the gears 174 and 175.

The entire set of gears 173, &c., are inclosed 95 in a circular casing or shield 315, preferably made of sheet metal and having near each end a suitable slot, as 316, (see Fig. 27,) of a width sufficient to let one of the two pawls of the two sets of pawls enter therein and engage the ratchet-wheel which it is designed 100 to actuate, and by moving this casing longitudinally the said openings may be put in the range of movement of either of said pawls, so that they in their stroke may engage either of the sets of ratchet-wheels to rotate the 105 shafts 168 or 171 intermittently in one and then in the other direction, another or third position of the casing 315 preventing any of the pawls from engaging any of the ratchet-wheels, as when the machine is doing circular 110 work and the curb 112 is lowered, the pawls then resting on the bridge m .

The casing 315 may be designated aptly as a "pattern" casing or shield, and it is secured for strength to disks n n , surrounding the 115 hubs of the bevel-gears referred to, the said disks having openings at their centers large enough to permit them to slide unobstructedly in the movement of the casing. The casing has in this instance of my invention a stud n' , embraced by a lever n^2 , mounted pivotally on a stud n^3 and having at its outer end a suitable link n^4 , which is connected to a suitable finger n^5 , adapted to be struck at the proper times and moved by a protuberance 120 on one of the links of the pattern-chain 61.

I have herein shown and described an improved and novel mechanism for imparting the necessary intermittent movements step by step in one and then in the opposite direction to the bars of the shogging or racking mechanism; but this present invention is not limited to the exact means shown, although the best known to me for moving the same,

and I may instead employ any other usual or suitable mechanical devices.

The depending portions 102 of the spider have suitable projections 210, (see Fig. 10,) 5 upon which may rest the lifting-circle 212, said lifting-circle have jointed to it at suitable intervals, as at 213, (see Fig. 5,) the lower ends of struts 214, which in turn are jointed at their upper ends to studs or projections 215, connected to or forming part of the curb 112, and the curb derives its vertical movement by imparting a partial rotary movement to the lifting-circle 212 to carry the pivotal point of the struts 213 to the right, as represented by dotted lines in Fig. 5, the rotation of the curb being restrained at such time by reason of the projections 110 in the slots 109, before referred to. To move this lifting-circle 212, I have provided it with a slot 216, 20 (shown in Fig. 8,) in which may enter a toe 217 (shown best in Figs. 16 and 17) at the upper end of a lever 218, having a cam projection 219, and entering by its lower end loosely and being guided in a hole in a cross-brace 220 of the framework. The lever 218 is connected by a stud-screw 221 with a fulcrum-lever 222, mounted upon a stud 223, (shown partially by dotted lines in Fig. 16,) 25 which is screwed into a hub 224, fast on the bearing-brace 107, said fulcrum-lever having a cam-toe 225.

I have combined with the levers 218 and 222 a cam 226, which is applied to the shaft h^{12} , before described, so as to be slid thereon, 30 the hub of said cam in this instance of my invention sliding on spline-pins 227, connected to a collar 228, adjustably secured to said shaft, as by a set-screw, as shown, the use of the collar and spline-pins enabling the splines 40 to be adjusted about said shaft, to thus put the working-surface of the cam 226 in exactly the proper position.

It will be obvious that when the cam 226 acts against the cam projection 219 of the lever 218 the lifting-circle (see Fig. 3) will be moved from the position therein shown to the right to lift the curb and that when the cam 226 is in position to strike the cam-toe 225 of the fulcrum-lever 227 the lever 218 will be 45 moved in the opposite direction to bring the lifting-circle back into the position shown in Fig. 3 to lower the curb, this being done when reciprocating knitting is to be stopped and circular knitting is to be commenced. To 50 move this cam, its hub will be suitably slotted to be embraced by the forked end of a lever 229, pivoted at 230 on a suitable part of the framework, a part of said lever being engaged by a link 231, (see Figs. 3 and 15,) jointed to 55 an arm 232, fixed to a vertical rock-shaft 233, having at its upper end an arm 234, having a pin which is engaged with a lever 235, having its fulcrum at 236 in a suitable stand 235^x, attached to the framework, said lever having 60 at its rear end a suitable rod 237, which is connected to a lever-like finger b^{42} , that at proper times will be acted upon by a suitable

roll or projection carried by said pattern-chain 61, said finger b^{42} also moving the switch-bar b^2 , instrumental in effecting the thread 70 change, as will be described.

The lever 235 is acted upon by a spring 238, (see Fig. 15,) which serves to normally hold the rock-shaft 233 in such position (see Fig. 15) that the shoe e^{14} , pivoted to the end of the arm 75 232, stands at one side of the range of movement of roll 22 during circular knitting, and when said lever 235 is moved to effect the raising of the curb, as described, the said shoe is swang aside and put in the range of movement of the roll 22, so that it will strike the shoe and cause the coupling-pin 21 to enter the notch in the vibrator h^6 , to thus effect the reciprocation of the cam-ring. The shoe has connected to it a rod 264, surrounded by a 80 spring 265, contained in a hollow arm 266, fast on the lower end of rock-shaft 233, said spring normally acting to keep said shoe pressed toward the flange 23^x of wheel h^3 .

The ring 104 of the spider receives in it the 90 neck A^2 of the conical needle-bed, the said neck being connected to said ring by suitable screws 260, (see Fig. 5,) and surrounding this neck loosely so as to slide about it is a ring 261, having cut upon it at its under side a series of bevel-teeth 262, which are engaged by the teeth of the bevel-wheel B^3 , before described.

The ring 261 has a flange provided with suitable holes to receive a series of screws 263, 100 said screws being extended through an outwardly-turned flange at the lower end of the cam ring or plate B' .

The cam-ring is a rather difficult member of the machine to manufacture, and it may be 105 made of less weight and more quickly by omitting from it the bevel-teeth with which it is usually supplied and by making the cam-ring detachable from the ring 261, having the teeth. The cam-ring can be taken off without 110 unmeshing the teeth 262 from its driving-wheel, which is a matter of very considerable convenience.

Referring now to the cam ring or plate B' , (shown as of conical shape,) it has a detachable 115 section 267, (shown enlarged in Figs. 12 and 13, Fig. 12 showing the outer side of the section and Fig. 13 the inner side thereof.) This section contains, as illustrated in the present embodiment of my invention, a pivoted directing-cam a^{18} , points a^7 and a^8 pointing toward each other and leaving a space between them, in which may be moved the directing-cam, the directing-cam closing one or the other of the crossings from the non-knitting or topping 120 groove a^9 into the knitting-groove a^{30} , the points a^8 a^7 in this instance of my invention being pivoted, as described of the guiding-gates in the patent referred to, and being moved positively by appliances at the outside 125 of the plate, as before described, different devices, however, from those employed in the 130 said patent.

The detachable section 267 is suitably

grooved for the reception of slides a^{23} and a^{25} , provided with drawing-down cams, one of said slides, as a^{23} , having a pin extended outwardly from its back, which is engaged by the tension-lever c , having a screw to regulate the position of the slide. I have shown the said tension-lever as provided with a spring 268, interposed between the end of the screw and the top of the raceway, to thereby obviate one trouble arising from the wearing of the screw or of the raceway, and also reducing friction upon the raceway.

The slide a^{25} has a suitable pin or projection, which is extended outwardly through the section 267, where it is engaged by a slotted plate 269, by which to enable the said slide to be adjusted as desired, according to the length of stitch required, it being remembered that the drawing-down cam on the slide a^{25} acts on the needles only in heel-and-toe work and when the cam-ring is moving in the direction opposite that in which it moves for circular knitting. The section 267 also has connected to it usual steel plates a^{13} a^{14} to elevate the needles, and switches a^5 and a^6 are employed to prevent the passage of butts of needles from the non-knitting or topping groove into the knitting-groove, but to let said butts pass freely from the knitting into the non-knitting groove.

The section 267, below the points a^7 a^8 , has fixed to it a plate a^{12} , provided with a lip a^{15} , located in line with the directing-cam a^{18} , said lip being provided with a concave face opposite the directing-cam, the curve of said concavity being described substantially from the center of oscillation of the directing-cam, the points a^7 and a^8 being shielded by the shoulders at each of the sides of said lip when the said points are down, as when the needles are being moved from the knitting into the non-knitting cam-groove during widening and narrowing, substantially as in said patent.

This invention is not limited in all instances to imparting positive movements to the points a^7 a^8 , and the same effect might be produced by positively oscillating the directing cam a^{18} .

The section 267 is attached to the cam-ring by suitable screws 270, and at each end of said section I have attached by screws 400 (see Fig. 4) blocks 401, the removal of either of said blocks leaving a space between the said section and the body of the cam-ring, through which a needle may be taken out or a needle put in in usual manner.

The cam-ring (see Figs. 4 and 11) has set upon it the slotted foot of a stand 271, the said foot being frictionally mounted on the said cam-ring by means of screws 272, extended through a thin steel plate 273, laid upon the said foot, the screws passing through a slot 274 in the said foot.

In Fig. 11 the friction plate has been broken out to show the slot below it.

The extent to which the foot may be moved on or with relation to the cam-ring, or the extent that the cam-ring may be moved after

the foot comes to rest, is determined by means of adjustable stops 284, attached to the cam-ring. The frictional stand 271 receives a cross-bar 276, pivoted at 277, receiving at its other end a movable bolt or stud 278. The cross-bar 276 receives the screw-threaded shank 279 of the cone-shaped thin metallic thread-rest d^{31} , common to the said patent, 75 said shank having upon it at opposite sides of said bar suitable nuts by which to adjust the shank longitudinally in said bar to properly center the thread-rest d^{31} to the upper ends of the needles used in the machine. The shank 279 referred to supports an arm 280, upon which are mounted suitable sheaves 281, about which the thread or yarn going to the needles is passed, said yarn also being passed preferably between roller-studs 282, fixed on 85 said thread-rest. The thread-rest and thread-guide 280 281 perform in this machine the same purpose and function with relation to the needles arranged in the conical bed as fully described and provided for in the said 90 patent.

I have shown the frictionally-supported stand 271 as provided with a tail-piece 283, which in the rotation of the cam-ring may strike the stops 275, made as pins set in holes, 95 thus shifting the relative positions of the thread-guide with relation to the knitting-cams, in order that the thread to be delivered to the needles when narrowing and widening is being done may be properly presented to the first needle to knit in the course to be made, and preferably I mount on the cam-ring (see Fig. 4) stops 284, between which the stand 271 slides.

I have herein shown (see Fig. 14^a) the sinker-actuating ring A^7 as provided with adjustable shoes w to bear on the upper end of the projection A^6 of the needle-bed, said shoes being acted upon by screws w' , the rotation of which enables the cam edge w^2 of the said ring to be raised or lowered with relation to the fulera of the sinkers to thus give to the sinkers the proper stopping and starting point in their movements. The shoes are guided by pins w^3 , extended through the ring, and the set-screws have combined with them suitable locking devices. (Shown as springs w^4 .) The sinker-actuating ring has a removable gate a^{33} to enable a sinker to be taken out or put in.

The shogging-bar b^9 has fast on it two adjustable cam projections 115 116, the projection 115 being in the range of movement of the arm 117, while the projection 116 is in the range of movement of the arm 118. The bar b^6 , the inner one, is provided with two adjustable cam projections 114 and 113, the projection 114 being the lowest and in range of movement of the arm 117, while the cam projection 113 is in the range of movement of the arm 118. The two cam projections 115 and 116 are set close together, because the heels or parts of the arms 117 and 118 nearest the fulcrum-stud s^2 meet them; but the pro-

jections 113 and 114 are separated somewhat one from the other, because the toes or points of the said arms contact with them. The projection 115 is lower than the projection 116 and its point goes under and overlaps the projection 116.

When the knitting is to be changed from circular or roundabout to reciprocal knitting for heel and toe work, the curb 112 is raised quickly, as stated, while the cam-cylinder is moving in the direction of arrow 1, and the easing 315 is moved to let the pawls referred to, on the pawl-carriers 302 and 303, act to commence and move the projections 113 and 114 toward the projections 115 116 to thus narrow course after course until the narrowest course for the heel or toe has been knitted, the first course on less than the whole number of needles for narrowing being knitted when the cam-cylinder is moving in the direction of arrow 2, and, the narrowest course having been knitted, the said pairs of cam projections are gradually separated course after course until the widening complementary to the narrowing has been completed and circular work is to be resumed. The instep-needles are located at the side of the machine. (Shown at the top of Fig. 4.)

When the cam-ring is being moved for reciprocal knitting in the direction of arrow 1, Fig. 4, the heel of arm 117 meets the cam projection 115, shifts the lever 119 to the right in Fig. 4, and moves the points to run the needles from the knitting into the non-knitting groove, and thereafter the movement of the cam-ring is continued in the same direction until all the needles have their butts in the non-knitting groove. Then the cam-ring is reversed, (see arrow 2,) and as the heel of arm 118 meets the cam projection 116 and restores the lever 119 to the position, Fig. 4, the points are shifted up to the directing-cam to thus catch the first needle of the number to knit in the course then to be made. Now, as the cam-ring is moved in the direction of arrow 2, Fig. 4, the arm 118 passes over cam projection 113; but the point of arm 117 hits cam projection 114, and thus again shifts the points to effect the putting of the butts of all the needles in the further movement of said ring in the direction of arrow 2 into the non-knitting groove, and this done the cam-ring is reversed, and on its movement again in direction of arrow 1 the point of arm 118 meets the cam projection 113 and causes the points to be moved to bring the desired number of needles from the non-knitting into the knitting-groove.

The movement of the rings with their cam projections toward each other for narrowing and away from each other for widening is effected substantially as the cam-cylinder completes its stroke in either direction.

The sinker cam-ring A⁷ has a projection t, which is acted upon by horns t' of stop-plates t², connected to the cam-ring B' by screws t³.

The shipper-lever g² may be moved by hand

through the hand-lever t⁵, rock-shaft t⁶, and slotted arm t⁷, embracing the shipper-lever.

To keep the rack-bar b⁹ from rising in the curb 112, it is grooved at its outer side as at o, (see left of Fig. 5,) and said groove is entered by the inturned lip of a plate o', (see Fig. 1^a,) attached to the outer side of the curb 112 by a suitable screw, said lip being extended through a slot in the curb, as shown in Fig. 1^a. To keep the rack b⁶ from rising in rack b⁹, the inner side of rack is also grooved, (see Fig. 5,) and said groove is entered by a plate or lug o², attached to ring b⁶ by a screw o³. 80

H represents the frame of the thread-presenting mechanism, it being shown as provided at one end with hubs H', mounted loosely on a rotating-shaft H², having bearings in a cross-head H³, adjustably mounted by screws H⁴ on vertical rods connected rigidly to and forming part of the framework of the knitting-machine, said frame H having laterally-extended arms H⁵ H⁶, connected, as shown, by a post H⁷. This cross-head H³ has 90 projections H⁸, on which rest the feet or projections H⁹ (see Fig. 19) of the frame H when in working position.

The shaft H² has fast on it a cam-hub H¹⁰, provided with two annular grooves 2 3, connected by cross-grooves 4 5, each pair of annular and cross grooves having combined with them a suitable switch, (herein marked b' b, both shown as secured to a rod b².) which is adapted to be slid at right angles to the grooves 2 3, 100 or parallel to the shaft H², one or the other of the said switches lying in and stopping or bridging part of one or the other of said annular grooves 2 3, as best represented in Fig. 21, where the switch b' stops the annular groove 2, one or the other switch being made to stop a groove, according to the position in which it desired to keep the lever C, pivoted at C^x, and provided at its outer or free end with a toothed segment C', said segment engaging a pinion a⁸ on the hub of a gear a⁶, which engages the gear a⁵, to be described, fast on the hollow shaft a, common to said patent, the movement of the lever C effecting the rotation of the shaft a in one and then in 115 the opposite direction.

The rear end of the lever C is provided with a pin or stud 300, having at its lower end a shoe 6, which runs in the grooves of the hub H¹⁰. The grooves in the hub H¹⁰ and 120 the switches b' b, co-operating therewith, are such as to enable the shoe to stand for a longer or shorter time in one or the other of said annular grooves 2 or 3, the hollow shaft a, carrying the thread-arms a' a², being then 125 at rest with one or the other, or it may be both, the said arms supplying thread, said thread or thread passing from the eye or eyes of the thread arm or arms a' a² to a suitable thread-guide 281, located substantially above the center of the needle-bed; but when the lever C is to be moved to rotate the shaft a and twist the two threads in the thread-arms together, preparatory to using 130

either the main thread m^{10} or the splicing-thread n^{10} or the main thread and reinforcing-thread, then the slide-rod b^2 will be moved to cause the switch nearest the annular groove 5 in which the shoe 6 then rests to enter said groove, so that the point of the switch will pass to the outer side of the shoe as the cam rotates, and will cause the switch to enter one of the cross-grooves and pass entirely into 10 the other annular groove, such movement rotating the shaft a and the thread-arms to twist the thread; but before such rotation takes place the thread-arm having the thread being used is moved, as will be described, to 15 cause its thread to be carried laterally in between the rolls d and d' , common to said patent, and put it against the other thread next to be used, and then held out of action between said rolls, and the two threads are 20 twisted together, so that the then active thread may engage and carry with it the inactive thread, and later the thread which is not to be used will be cut off, as will be described.

In Fig. 21 the shoe is shown in the groove 25 3, and to cause said shoe to enter the groove 2 the switch b must be moved to the right. The movement of the switch-carrier b^2 is determined automatically by a switch-changer (shown as a slide-bar b^{60}) having two horns b^7 30 b^8 , said bar having, as shown, projections b^{90} b^{100} , between which plays one end of the finger or lever b^{42} , acted upon in practice, as before described, by a suitable projection on the pattern-chain. Preferably the projections b^{90} b^{100} will be adjustable on the bar b^{60} , and by shifting said bar just in advance of the time it is desired to move the lever C one or the other of the horns b^7 b^8 will be put into working position to be struck by the switch-carrier 35 b^2 , the latter as soon as it in the rotation of the cam meets a horn being slid in the cam-slot.

The shaft H^2 has fast to it at one end (see Fig. 21) a bevel-gear b^{14} , which is engaged and 40 rotated constantly by the bevel-gear b^{15} , fast on a vertical shaft b^{16} , having suitable bearings b^{17} , the lower end of said shaft being in practice provided with a bevel-gear b^{18} , Fig. 2, which will be driven from a suitable pinion 45 b^{19} , mounted on a stud b^{20} , Fig. 3, said pinion being engaged by the gear h' , fast on the continuously-rotating shaft e' .

The gear a^6 referred to has attached to it an arm c^x , (shown best in Fig. 22,) provided with 50 two horns 10 12, each of which when said gear is at its extreme stroke acts on the lever c' of the two like levers c' c^2 , common to said patent, and pivoted on the arm H^5 of the frame H, said levers having at their lower ends like 55 cam-segments 13, which are adapted to be struck by pins 14 at the upper ends of the thread-arms a' or a^2 , pivoted on the head 16 of the shaft a , the particular pin to strike the segment depending upon which thread-arm is 60 at the front and is to have the thread carried by it removed from between the feed-rolls.

When the thread-arms a' a^2 are merely to

present a knitting and a splicing thread, as required, to be knitted, one to the exclusion of the other, in a stocking, then the lever c^2 70 may be omitted, but it will be required when it is desired to insert into the work with a main thread a reinforcing-thread.

Whenever a pin or projection 14 of the thread-arm meets a cam-segment 13, the 75 thread-arm will be thrown outwardly away from the center line of the shaft a and the thread carried by the arm will be removed from between the rolls d d' and the thread of said arm so moved out will go to the needles 80 and be knitted into the fabric.

In Fig. 19 the thread in arm a' is supposed to be going to the needles, while the thread in the arm a^2 has its free end held between the said rolls. Now, if it is desired to use the 85 thread of arm a^2 , the lever C will be started and start the gear a^6 , and with the gear starts the arm c^x , and the horn 10, then holding the lever c' , will retire quickly from said lever, letting the then contracted U-shaped wire 90 spring 416 expand and act quickly to move the arms toward each other and put the thread n^{10} in the arm a' between the rolls d d' , and as the said running thread n^{10} is brought against the stationary thread m^{10} , then held 95 between said rolls, the rotation of the shaft a will cause the two threads to be twisted together, so that the running thread will catch and drag the other thread with it, and as the gear a^6 completes its movement the horn 12 100 of the arm c^x will again meet the lever c' and throw its lower end inwardly, so that the projection 14 of the thread-arm a^2 , then being brought to the front, is moved to lead the thread m^{10} out from between the rolls, and 105 the other thread left in the rolls is cut off, as will be described, close to the lower side of the rolls.

The journals of one of the thread-rolls (herein shown as the roll d) are supported in 110 a carrier d^2 , mounted loosely on part of the arm H^6 of the frame H, said carrier being acted upon by a very delicate spring d^3 , thus enabling the roll d to be pressed slightly toward the roll d' , such construction enabling 115 the rolls to readily adapt themselves to the thickness of the thread and hold and control the same better than when the said rolls are in fixed bearings.

The frame H has a cutter-actuating lever 120 D, suitably pivoted thereon at D', and having at one end a pivoted shoe 22^x, (shown by dotted lines in Figs. 19 and 20,) it entering and traveling in the grooves of the hub H^{10} , as described, of the shoe 6, the shoe of lever D following in the same path as the shoe of lever C, for immediately the lever C has been moved to effect the rotation of the hollow spindle a to twist together the threads carried by the arms a' a^2 , and has then separated the arms, 125 the lever D must act to effect the cutting off of the thread which is not to be used. The lever D has at one end a segmental series of teeth D^2 , which engage the teeth of a pinion 130

D³, mounted on a stud D⁴, the hub of the pinion having a shear-opener. (Shown as composed of two pins 18.) The shears are composed of blades at the ends of two arms e e', 5 pivoted at e⁸, the long arms of the said blades being normally held toward each other by means of a suitable spring e².

When the lever D is moved to rotate the gear D³ from the position, Fig. 20, the said pins 18 act on the arms e e' of the shears, separate said arms and close the cutting ends of the shears upon the thread then between the blades of the shears. Now, if it is desired in a heel or toe or at any point to insert a reinforcing thread and let it be knitted into the stocking or fabric with the main thread, I have only to remove the arm c^x and put in place of it the arm c^{2x}, (shown in Fig. 24,) it differing from the arm c^x only in that it has an extra horn 20. The extra horn works in unison with the horn 12, and when horn 12 is in position to act on the lever c' and keep a thread-arm out the horn 20 acts on the lever c² and keeps the other thread-arm out, the threads 25 from the arms a' and a² then passing the rolls d d', one at one end and the other at the other end thereof.

When the threads are in the last position referred to and the shears are closed, there is no 30 thread between them to be cut off, and consequently both threads go into the work.

Having described my invention, what I claim as new, and desire to secure by Letters Patent, is—

35 1. In a knitting machine, the following instrumentalities, viz:—a needle-bed, a ring or plate provided with needle selecting devices and actuating cams, a vertically movable curb, and rack bars therein having surfaces 40 to co-operate with the instrumentalities employed for moving the needle selecting devices carried by said ring or plate, means to raise and lower said curb, and means to move said rack bars in opposite directions in said 45 curb, substantially as described.

2. The table-top having the spider, and the circular curb, the circular rack bars contained therein, and means to move said rack bars in said curb, combined with devices under the 50 control of a pattern surface to raise and lower said curb and its contained rack bars, for the purposes set forth.

3. The circular curb, a lifting circle, and a series of links connecting said curb and circle, and guides for the curb, combined with devices to partially rotate said circle to raise and lower the curb, substantially as described.

4. The circular curb, the lifting circle, links connecting said circle and curb, and the levers 55 218 and 222, combined with a cam, and means to rotate and to slide said cam on its shaft to act upon one or the other of said levers to effect the movement of the lifting circle in one or the other direction, substantially as described.

5. In a circular knitting machine, the curb 60 112, the rack bars therein having teeth, and

means to raise and lower said curb, combined with shafts having gears to engage each of said rack bars, and to remain in engagement therewith in all positions of the curb, substantially as described.

6. In a knitting machine, a conical needle-bed, a conical needle actuating cam-ring surrounding said bed and provided with needle actuating cams, and having crossing knitting and non-knitting grooves, and needle-selecting mechanism including an inclined or heart-shaped cam, and points directed toward each other; two circular rack bars each provided with two cam projections, means to move said rack bars, a lever having arms 117 and 118, and carried by said needle-actuating cam-ring and adapted to strike the cam projections on said rack bars to thereby change the relative positions of the directing cam and points automatically to effect the passage of the desired number of needles from the non-knitting into the knitting groove and back again preparatory to knitting a second course, substantially as described.

7. A cam ring having a knitting and a non-knitting groove, one crossing the other, needle selecting devices arranged at the crossing of said grooves and having two points pointed one toward the other, and a directing cam, and having usual knitting cams, a lever mounted on said cam-ring and having arms 117 and 118, and devices intermediate said lever and said selecting devices to move them, substantially as described, and means to reciprocate said cam-ring, combined with two rack bars each provided with a pair of cam projections, and means to move said rack bars one about the other in opposite directions, said arms acting directly on said cam projections to move the selecting devices carried by the cam ring to effect the movement of the butts of all the needles into the non-knitting groove after the completion of a reciprocal course, and to then at a reverse movement of the cam-ring take from the non-knitting groove a defined number of needles for the next reciprocal course to be made, as set forth.

8. The curb, means to raise and lower it, the rack bars carried thereby, and the extension 112^x, the shafts 163 and 164 carried by said extension and provided with gears to engage the rack bars; combined with two shafts 168 and 171, gearing connecting the same with said shafts 163 and 164; gears to rotate shafts 168 and 171; a series of pawls and ratchets; a shield; means to move said pawls, a pattern surface and devices intermediate said shield and pattern surface to move the shield and determine which of said pawls shall engage said ratchet wheels, substantially as described.

9. Two shafts 163 and 164 having co-incident centers of rotation, worm toothed wheels carried thereby, shafts 168 and 171 having worms and bevel gears 169 and 172 attached to said shafts, combined with a pair of gears for each

of said bevel gears, a ratchet wheel attached to each gear of the pairs of gears; a series of pawls, one for each ratchet wheel; means to move said pawls; and a shield to permit as 5 desired the proper pawls to engage said ratchet wheels to rotate the shafts 168 and 171 in either direction and in directions reverse one of the other, substantially as described.

10. The thread holding rolls, a pair of shears having its pivot mounted near said rolls, a pinion having devices to co-operate with the arms of said shears, and a sector lever for rotating said pinion, combined with a rotating hub having annular and crossing grooves, 15 switches in said grooves, and means to support and move said switches, substantially as described.

11. A frame, a hollow spindle mounted therein and provided with thread arms, devices to rotate said spindle to twist the threads and move said thread arms toward and from each other, said devices including a sector lever C, combined with a pair of shears pivoted 20

on said frame, a pinion provided with shear opening devices, a sector lever, as D, and a 25 hub or cylinder provided with annular and crossing grooves to receive pivoted shoes carried by said levers, and a switching device, to operate, substantially as described.

12. A frame, a hollow spindle having thread 30 arms, a pair of shears, a rotating grooved hub, its switches b, b', a switch rod b² to which they are secured, the sector levers and connections actuated by said hub for moving the said hollow spindle and actuating said shears, combined with a switching bar having horns, a lever or arm, as b⁴², and a pattern surface to move said lever, substantially as described.

In testimony whereof I have signed my name to this specification in the presence of 40 two subscribing witnesses.
